ERNEST DAVIS, OF SYRACUSE, NEW YORK, ASSIGNOR TO THE PROSPERITY COMPANY INC., OF SYRACUSE, NEW YORK, A CORPORATION OF NEW YORK

WASHING APPARATUS

Application filed April 7, 1927. Serial No. 181,869.

This invention has for its object a washing apparatus particularly applicable for commercial laundries, by which clothes receptacles containing the clothes to be washed are moved successively from one operation to another without handling or loading and unloading the clothes whereby the washing operation is continuous.

The invention consists in the novel features 10 and in the combinations and constructions hereinafter set forth and claimed.

In describing this invention reference is had to the accompanying drawings in which like characters represent corresponding parts 15 in all the views.

Figure 1 is a side elevation of this washing apparatus.

Figure 2 is an end elevation looking to the right in Figure 1.

Figure 3 is an enlarged end elevation showing the operating means for the carrier.

Figure 4 is an enlarged fragmentary elevation of the vat carrier and contiguous parts.

Figure 5 is an enlarged sectional view through one of the clothes receptacles and contiguous parts of the carrier.

Figure 6 is an enlarged sectional view through one of the washing vats.

Figure 7 is a side elevation of the apparatus generally a series of washing vats, a series of clothes receptacles, and means for effecting relative movement of the series to bring the clothes receptacles into and out of the vats.

More specifically it comprises a series of washing vats or vats having some form of washing machine mechanism associated therewith, an endless series of clothes receptacles or baskets movable to bring the receptacles into 40 juxtaposition to the washing vats, and one series being movable toward and from the other to bring the receptacles into and out of the vats.

In the illustrated embodiment of my invention the series of washing vats are movable vertically toward and from the clothes receptacles or baskets in line therewith.

1 designates the series of vats mounted upon a vertically movable carrier 2, each vat having a washing mechanism as 3 (Figs. 4 and 6)

associated therewith. The vats are practically unobstructed on their interior and have their tops open. The washing machine mechanism acts primarily to circulate the washing fluid and the clothes, and force the fluid through the clothes. The washing machine mechanism may be of any suitable type and is usually of the type shown in Cowles Patents No. 1,545,081, dated July 7, 1925, and No. 1,545,082, dated July 7, 1925.

4 designates the clothes receptacles, which are arranged in a series to move successively into alignment with the vats 1. These clothes receptacles 4 are supported by a suitable endless carrier consisting of tracks 5 and an endless belt for moving the receptacles 4 along the track.

As here shown the baskets or clothes receptacles 4 are provided with trucks or wheels 6 movable along the track 5, which is in the form of inwardly or oppositely facing channels, as shown in Figure 5.

A belt or cable carrier 7 runs over pulleys or sprockets 8 and 9 at opposite ends of the track, one of the pulleys being connected to driving means. The carrier 7 is arranged so that the receptacles move in upper and lower runs whereby the clothes can be loaded into the receptacle while they are on the upper run, and the receptacles are in line with the washing vats when they are in the lower run. Each receptacle 4 is formed with an arm 10, which is connected to the cable in any suitable manner as by a screw 11, and the pulleys are formed with notches 12 for receiving the ends of the arms 10. The baskets or clothes receptacles 4 are also formed with openings 13 in the walls thereof arranged to come into alignment with the inlet and outlet jets of the washing machine mechanism 3. Also each clothes receptacle 4 is formed with a dumping door 14, which is on the top side thereof when the receptacles move along the upper run of the carrier, and on the bottom side when the receptacles move to the lower run of the carrier. These dumping doors are preferably hinged at one edge and so arranged that they swing open as the receptacles move around the pulley 9 from the lower run to the upper run of the carrier.

A suitable platform or floor 15 extends along the upper run of the carrier from which the clothes can be loaded into the receptacles 4 while these receptacles are on the upper run 5 of the carrier.

The series of vats 1 extend along only a part of the length of the lower run of the carrier 7, and receptacles such as hydro extractors 16 are arranged to receive the clothes 10 from the receptacles after they have passed through the various washing vats, the clothes being dumped from the receptacles 4 on the lower run of the carrier by unlatching the doors 14 when the receptacles come opposite 15 the extractor or extractors 16.

The carrier 2 for the washing vat is raised and lowered by any suitable power operated jack mechanism. As here shown the carrier is provided with depending rack bars 17 extending through suitable guides or pedestals 18, and formed with rack teeth 19. These rack bars 17 are operated by shafts 20 having pinions 21 at their ends meshing with the racks, the shafts 20 being driven from any 25 suitable source of power through differential gearing 22.

The pulley 8 is actuated to drive the carrier belt 7, from a shaft 23 which is connected to any suitable source of power and has a worm 24 thereon meshing with a worm gear 25 mounted on a shaft 26 supported by any suitable frame work. The shaft 26 has a pinion 27 thereon meshing with a gear 28 mounted on a shaft 29 on which the pulley 8 is mounted. The shaft 29, and also the shaft on which the pulley 9 is mounted, are supported in any suitable frame work.

The cable 7 is intermittently operated, the intermittent operation being controlled in any suitable manner. Also the operation of the shafts 20 is controlled in any suitable manner. The control thereof forms no part of this invention, and it is only necessary for an understanding of this invention to bear in mind that the cable 7, and the carrier 2 are operated intermittently at the will of the operator.

As will be understood by those skilled in the art, in washing clothes, the clothes are subjected to several different washing operations or washed in different washing fluids, and in the machine here illustrated there are twelve washing vats into which each clothes receptacle 4 is moved consecutively, although some of the vats may contain the same kind of washing fluid.

In operation the clothes are loaded into the receptacles 4 while the receptacles are on the upper run of the carrier, and after being loaded in, the dumping doors 14 are closed and latched. The carrier 7 is then started and moved one step when another empty receptacle which has been brought to the upper run of the carrier by such movement of the carrier is loaded and the carrier actuated

another step. Eventually the first loaded receptacle comes opposite the first vat of the series of vats 1, and when opposite or in alignment with the same, the carrier 2 is operated to bring the receptacles on the lower run of the carrier into the vats, where the washing operation is performed. During each successive step the receptacles 4 move step by step through the series of washing vats 1, and as they are carried beyond the end of the series of washing vats, the doors 14 are unlatched by an operator so that the clothes can dump into a receptacle, preferably an extractor 16. After the operation is once started, it is continuous and a minimum 80 handling or loading and unloading of the clothes is required. The classifying and identifying of the various bundles of clothes forms no part of this invention, but usually each washing receptacle contains a certain class of laundry of one customer and the next receptacle another class of laundry of the same customer. Usually no single receptacle contains the clothes of more than one customer. However, the classification and the identification of the clothes form no part of this 90 invention.

What I claim is:—

1. A washing apparatus comprising a series of washing vats, a series of clothes receptacles, an endless carrier, arranged so that opposite runs thereof extend horizontally, the receptacles being connected to the carrier to move into and out of alignment with the vats, and means for moving one series toward and from the other when the receptacles are in line with the washing vats and thereby bringing the receptacles into and out of the vats. 95

2. A washing apparatus comprising a series of washing vats, a series of clothes receptacles, a carrier comprising an endless track having upper and lower runs extending in horizontal directions, the receptacles being movable along the track into and out of alignment with the series of vats, and an endless belt connected to the receptacles to move them along the track, and means for moving one of said series toward and from the other to bring the receptacles into and out of the vat. 100

3. A washing apparatus comprising a series of washing vats, a series of clothes receptacles, an endless track having upper and lower runs extending in horizontal directions, the receptacles being movable along the track into and out of alignment with the series of vats, an endless belt connected to the receptacles to move them along the track, a second carrier for supporting the washing vats below the lower run of the track, and means for moving the vat carrier toward and from the lower run of the track to bring the receptacles on such lower run into and out of the washing vats. 115 120 125 130

4. A washing apparatus comprising a series of washing vats having washing machine mechanism connected thereto, a carrier for the vats, a series of clothes receptacles, a carrier for the receptacles having different loading and washing levels and movable to carry the clothes receptacles from one level to the other, the carrier for the vats being movable toward and from the washing level of the carrier for the receptacles to bring the receptacles into and out of the vats.

In testimony whereof, I have hereunto signed my name, at Syracuse, in the county of Onondaga, and in the State of New York,
15 this 12th day of March, 1927.

ERNEST DAVIS.
